Inventor

Walter Greaves,
By his Attorney
Benjamin Roman.

UNITED STATES PATENT OFFICE.

WALTER GREAVES, OF ALAMEDA, CALIFORNIA.

FOUNTAIN-PEN.

1,290,545.

Specification of Letters Patent.

Patented Jan. 7, 1919.

Application filed September 28, 1917. Serial No. 193,708.

To all whom it may concern:

Be it known that I, WALTER GREAVES, a citizen of the United States, and resident of the city of Alameda, in the county of Alameda and State of California, have invented a certain new and useful Fountain-Pen, of which the following is a specification.

This invention relates to fountain pens. Heretofore, the caps that usually slip over the ink-barrels and cover the pen-points of fountain pens have been constructed to contain ink-tablets, to enable the user to make his own ink, by means of filling the ink reservoir with water and dissolving one of the tablets therein, and threaded plugs were provided to retain the ink tablets within the caps. This mode of making ink for the fountain pen is particularly utilized by travelers and military persons, who find it 10 convenient or impossible to carry along bottles of ink for replenishing the ink reservoir of the fountain pen.

The above mentioned cap construction is however found objectionable because the 25 cap or the threaded plug that closes up the ink-tablets therein, being detachable, is frequently lost, and the user is thus left often without a supply of the ink tablets.

The principal object of my invention is 30 to provide an improved fountain pen, wherein the aforementioned disadvantages are prevented, which embodies simple, inexpensive, and improved means for retaining the ink tablets, and which the user can utilize with convenience and safety.

Other objects and advantages will hereinafter appear.

In the accompanying drawings,—

Figures 1 and 2 are sectional elevations 40 of the fountain pen, showing its parts in different positions.

Fig. 3 is a perspective view showing a detail of the fountain pen on an enlarged scale.

The fountain pen comprises an ink barrel 45 1 having therewithin an ink reservoir 2 closed by an ink-feeder 3 carrying a pen 4, and a cap 5 fits over the extremity of barrel 1 to cover the pen 4 and feeder 3 and protect these parts in the usual manner. A 50 partitioning wall 6 at the bottom of reservoir 2 separates the latter from a tapped cavity or chamber 7 formed in the rear end 8 of the barrel 1, and a cylinder or receptacle 9, for holding ink tablets, having a threaded hub 10 and a manipulating knurled head 11, threads into the cavity 7. When

assembling the fountain pen, a split tapered collar 12, Fig. 3, which is preferably of hard rubber and flexible enough to open wide its slit 13 and to completely close the slit, is 60 slipped over and around the cylinder 9 to a position adjacent the head 11, and then the cylinder 9 is threaded into the chamber 7 to about the position shown in Fig. 1. The collar 12 is then pressed into the chamber 65 7, between its tapped wall 14 and the cylinder 9, to the position shown, Figs. 1, 2, wherat the collar springs outwardly and bears against the tapering wall 15, of a counterbored portion 16, with its edge 17 lodging 70 against a ledge 18 formed by the meeting of walls 14, 15. Thereafter, the cylinder 9 may be threaded, by rotation of its head 11, into the chamber 7 to the position shown in Fig. 2 to completely close up the chamber, but 75 any unthreading of the cylinder 9 outwardly further than the position shown in Fig. 1 is prevented by the abutment of the end of its threaded hub 10 against the edge 19 of collar 12. The receptacle 9 may be loaded 80 with ink tablets 20 by unthreading the same to the position shown in Fig. 1 and inserting the ink tablets through an opening 21 in its wall 22 adjacent its head 11, after which the receptacle may be threaded back to the 85 position in Fig. 2 to thereby completely close the cavity 7 and effectively retain the ink-tablets 20 therein. To extract an ink-tablet from the receptacle 9, the same is unthreaded to the position shown in Fig. 1 90 and one of the tablets is taken out therefrom through the opening 21, and then the cylinder 9 may be threaded back to normal state to close the chamber 7 and seal the opening 21.

It will be evident that the abutment of the threaded hub 10 against the collar 12 permits unthreading of the cylinder 9 only partially and sufficiently far to enable extracting one of the ink tablets 20 through opening 21, whereby the receptacle 9 is rendered inseparable from the barrel 1 and accidental loss of the receptacle and of the ink tablets 20 contained therein is effectively prevented. To make the ink in reservoir 2, 100 it merely requires removing the feeder 3, pouring water into the reservoir, and then dropping the extracted ink-tablet into the water and closing the reservoir with the feeder 3. When writing with the pen the 105 cap 5 may be slipped over the rear of barrel 1 in the usual manner.

Variations may be resorted to within the scope of the invention.

Having thus described my invention, I claim:-

- 5 1. In a fountain pen, means for retaining ink tablets including an ink-barrel, said barrel having a cavity, means for closing said cavity adapted to be partially withdrawn for extracting ink tablets, and means
- 10 10 to prevent complete withdrawal of said latter means to insure against loss of the latter means.
- 15 2. A fountain pen having the combination of an ink-barrel, said barrel having a cavity, a receptacle within said cavity for the retention of ink tablets, having an opening for loading ink tablets thereto, said receptacle adapted to be partially withdrawn for extracting the ink tablets through
- 20 20 said opening, and means to prevent complete withdrawal of said receptacle to insure against loss thereof and of the ink tablets.
- 25 3. A fountain pen having the combination of an ink-barrel, said barrel having a cavity, a receptacle for ink tablets within said cavity having threaded connection with said cavity and adapted to be partially unthreaded for extracting ink tablets, and means to prevent complete unthreading of said receptacle to insure against loss thereof and of the ink tablets.
- 30 4. A fountain pen having the combination of an ink-barrel, said barrel having a cavity, a receptacle for ink tablets within said cavity having threaded connection with said cavity and an opening for loading ink tablets therethrough, said receptacle adapted to be partially unthreaded for extracting the ink tablets through said opening, and
- 35 40

means to prevent complete unthreading of said receptacle to insure against loss of the receptacle and of the ink tablets.

5. A fountain pen having the combination of an ink-barrel, said barrel having a cavity, a receptacle for ink tablets within said cavity, said receptacle adapted to be partially withdrawn from said cavity for extracting ink tablets therefrom, and means to prevent complete withdrawal of said receptacle to insure against loss thereof and of the ink tablets.

6. A fountain pen having the combination of an ink-barrel, said barrel having a cavity, a receptacle for ink tablets within said cavity, said receptacle having threaded connection with the wall of said cavity and an opening at the side thereof for loading ink tablets therethrough, said receptacle adapted to be unthreaded for extracting the ink tablets through said opening, and means to prevent complete unthreading of said receptacle to insure against loss of the receptacle and of the ink tablets.

7. A fountain pen having the combination of an ink-barrel, said barrel having a cavity, a receptacle for ink tablets within said cavity, said receptacle having threaded connection with the wall of said cavity and adapted to be partially unthreaded for extracting ink tablets therefrom, and a collar lining the walls of said cavity limiting the unthreading of said receptacle to insure against loss of the receptacle and of the ink tablets.

Signed at the city of New York in the county of New York, and State of New York, this 25th day of September, A. D. 1917.

WALTER GREAVES.
